UNITED STATES PATENT OFFICE.

MARIUS H. HANSEN, OF CHICAGO, ILLINOIS.

WEIGHING-SCALE.

1,248,106.

Specification of Letters Patent. Patented Nov. 27, 1917.

Application filed November 4, 1915. Serial No. 59,597.

To all whom it may concern:

Be it known that I, MARIUS H. HANSEN, a citizen of the United States, residing in Chicago, in the county of Cook and State of Illinois, have invented certain new and useful Improvements in Weighing-Scales, of which the following is a specification.

The purpose of the present application is to cover specifically the details in the construction of a scale which is covered generically, and shown as a modification, in a companion application (Case B) filed of even date herewith. In the application aforesaid the form which is elected as the preferred form has but a single load spring and the specific claims of said application relate to the features that are peculiar to a single load spring while the forms of the invention which are shown in the present application have two load springs and the claims of this application relate to features that are peculiar thereto.

In all forms of the invention, however, the load mechanism is independent of the casing to the extent that the casing sustains no part of the load, but is carried by the load mechanism so that its only function is to conceal and protect it and to support the dial, the pointer, and its shaft and pinion.

The invention consists in the features of novelty that are hereinafter described with reference to the accompanying drawing which is made a part of this specification and in which:—

Figure 1 is a front elevation of a scale embodying the invention with the dial and front of the casing omitted.

Fig. 2 is a vertical section thereof substantially on the line 2—2, Fig. 1, looking in the direction of the arrows.

Fig. 3 is a section on the line 3—3, Fig. 1 looking in the direction of the arrows—downward.

Fig. 4 is a perspective view of a plate for forming a swivel connection between the setting screw and the casing.

Fig. 5 is a perspective view of the so-called load-head.

Fig. 6 is a view similar to Fig. 1 showing some of the parts of modified form.

Fig. 7 is a vertical section thereof substantially on the line 7—7, Fig. 6.

Fig. 8 is a perspective view of the part shown in Figs. 6 and 7 for forming a swivel

connection between the setting screw and 55 the casing.

Fig. 9 is a perspective view of the load head of the modified form shown in Figs. 6 and 7.

The scale is of the suspension spring type 60 and has a hanger which, as shown in the drawing is in the form of a ring, 1. This hanger engages the so-called load head, 2^a, which is engaged, at equal distances upon opposite sides of its longitudinal vertical 65 center by the upper ends of suspension rods, 3, the lower ends of which engage washers, 4, which in turn engage convolutions near the upper ends of load springs, 5^a, in such manner that the washers may be adjusted up 70 or down, by turning them relatively to the springs, for regulating the length and therefore the tension of the active portions of the springs. The lower ends of the springs engage the upper end of a so-called draw- 75 bar or load-bar to the lower end of which is attached a hook, 7, to which the load is applied by any suitable device or devices such, for example as a scoop, pan or other device (not shown). Or the hook alone 80 may be used and the load applied directly to it.

When a load is applied to the hook it will draw the load-bar, 6, downward in opposition to the resistance of the springs, 5, and 85 stretch or distend the springs to an extent or distance exactly proportional to the weight so applied. This relation or condition is established by the proper adjustment of the washers, 4, in the well-known manner. 90

The load-bar, 6, has, at its upper end a portion, 7, of inverted U-shape and to this inverted portion is jointed the upper end of a rack-bar, 8, which engages a pinion, 9, rigidly secured to a shaft, 10, which is journaled in and supported by the dial, 11, and a bridge piece, 12, which is rigidly secured to the back of the dial so that when the load-bar, 6, is moved downward the rack-bar will cause the pinion to rotate clockwise and carry with it the pointer, 13, which is rigidly secured to the shaft, 10. The rack-bar is held normally in engagement with the pinion, 9, by a weight, 14, which is formed integrally with the rack-bar. 100

As above intimated the initial adjustment of the scale so that the pointer stands at zero when no load is on the hook, 7, is ac- 105

- complished by adjusting the washers, 4, upward or downward relatively to the springs, as may be necessary. After this first adjustment is accomplished it may become necessary to again adjust or reset the scale so that the pointer will stand at zero at the commencement of the next weighing operation. This may be necessitated by any one of a number of causes—as, for example, by applying to or removing from, the hook, 7, a scoop, pan, or other load receiving device. This readjustment or re-setting is accomplished by a setting screw, 5, which passes through offset portions, 6, and 17, of the load-head, 2^a, and has threaded engagement with one of said offset portions—say the portion, 17, the other of said offset portions serving simply as a guide and brace for sustaining the screw against lateral movement.
- 20 In the form of the load-head shown in Figs. 1, 2 and 5, these offset portions are formed by offsetting a portion of the metal plate of which the load-head is formed, while in the form shown in Figs. 6, 7 and 9, they are formed by a flange, 17^a, at the lower end of said plate and a lug, 16^a, formed by deflecting a portion of the plate at a point intermediate of its ends.

In both of these forms of the invention 30 the screw is provided near one of its ends with a circumferential groove, 18, for effecting a swivel connection between it and the casing, 20. This connection is completed by a part, having a U-shaped notch which receives the reduced portion of the screw, resulting from said groove, so that the part in which said notch is formed straddles the reduced portion of the screw.

As shown in Figs. 1, 2, 3 and 4, this 40 notched part is a simple plate, 19^a, which is riveted to the bottom, 20^a, of the casing while as shown in Figs. 6, 7 and 8 it is a flange, 19, of a substantially U-shaped part, 19^b, which is shown in perspective view in

45 Fig. 8, the details of which are fully shown and described in my application aforesaid.

In all of the several forms of the invention one end of the setting screw is notched or otherwise shaped to receive a screw-driver 50 or other implement for turning it. In the form of the invention shown in Figs. 6 and 7 the setting screw passes through an opening in the top of the casing, as it does in my application aforesaid, while in the form of 55 the invention shown in Figs. 1 and 2, the setting screw extends downward from the load head, completely through the casing, and passes through an opening in the bottom, 20^a, thereof. This is preferable in some 60 types of suspension spring scales.

The operation of the two forms of the invention is, generally speaking, substantially the same as that of the form shown in my application aforesaid, and need not be here 65 again described.

It may be said however, that the use of two load springs arranged at equal distances upon opposite sides of the central line of strain has certain advantages over a single load-spring arranged directly in said line. 70

What I claim as new is:—

1. A suspension spring scale having, in combination, a casing having openings through its top and bottom, a load-head passing through the top opening and slideable freely in said opening the portion of the load-head which projects above the top of the casing having means whereby it is suspended, adjustable means connecting the load-head and casing, whereby the casing 80 is supported by the load-head and relieved of sustaining any part of the load, a pair of load springs the upper ends of which are connected to said load-head, a load-bar to which the lower ends of said springs are 85 connected, said load-bar passing through the bottom opening and slideable freely in said opening and means for applying the load to the lower end of said load-bar.

2. A suspension spring scale having, in combination, a load head, a pair of load-springs, means connecting the upper ends of the load springs with the load-head at equal distances on opposite sides of its longitudinal center, a load-bar to which the 95 lower ends of said springs are connected at equal distances on opposite sides of its longitudinal center, means for applying the load to the lower end of said load-bar, a casing having through its top an opening 100 through which the load-head passes and is freely movable and having through its bottom an opening through which said load-bar passes, a setting screw having threaded engagement with the load-head, means 105 forming a swivel connection between the setting screw and casing, a pointer and means for transmitting movement from the load-bar to the pointer.

3. A spring scale having, in combination, 110 a pair of load-springs, a load head to which their upper ends are connected and by which they are supported, a load-bar to which the lower ends of springs are connected, means for applying the load to the lower end of 115 said load-bar, a casing, and a setting screw having threaded engagement with the load-head whence it extends downward completely through the casing, the bottom of the casing being provided with openings 120 through which the lower ends of the load-bar and setting screw pass.

4. A suspension spring scale having, in combination, a load-head consisting of a plate having offset portions, a pair of load 125 springs the upper ends of which are connected to said offset portions at equal distances on opposite sides of its longitudinal center, a draw-bar to which the lower ends of said springs are connected at equal dis- 130

tances on opposite sides of its longitudinal center, means for applying the load to the lower end of said draw bar, a casing, a setting screw having threaded engagement 5 with the load head, whence it extends downward completely through the casing, the bottom of the casing being provided with openings through which the lower end of the draw-bar and the setting screw pass, a

dial carried by the casing, a pointer, a shaft 10 carrying the pointer and in turn carried by the dial, and means for transmitting movement from the draw-bar to said shaft.

MARIUS H. HANSEN.
